United States Patent Office

Des. 187,383
Patented Mar. 8, 1960

187,383

JUVENILE VEHICLE

Glade L. Dalton, Lancaster, Calif.

Application May 25, 1959, Serial No. 56,062

Term of patent 14 years

(Cl. D34—15)

I claim:

The ornamental design for a juvenile vehicle, substantially as shown.
